CLAIM

The ornamental design of a meter socket, as shown in the figures and described.

DESCRIPTION

FIG. 1 is a front view of a meter socket of the present invention in one embodiment;
FIG. 2 is a right-side view of the meter socket of FIG. 1;
FIG. 3 is a left-side view of the meter socket of FIG. 1;
FIG. 4 is a top view of the meter socket of FIG. 1; and,
FIG. 5 is a perspective view of the meter socket of FIG. 1.
In FIGS. 1 through 5, contours are shown with thin grey lines.
Structure that is not part of the claimed design, but shows the environment in which the design is associated, is represented in the drawings by broken lines.

1 Claim, 5 Drawing Sheets
